CLAIM

The ornamental design for a fragrance bottle and cap, substantially as shown and described.

DESCRIPTION

FIG. 1 is a top, front and right side perspective view of a new design for a fragrance bottle and cap;

FIG. 2 is a front elevational view thereof, the rear, left side, and right side elevational views being identical except for the unclaimed bow portion;

FIG. 3 is a top plan view thereof; and,

FIG. 4 is a bottom plan view thereof.
